UNITED STATES PATENT OFFICE.

DANA K. MARSHALL, OF MANCHESTER, NEW HAMPSHIRE, ASSIGNOR TO
CHARLES F. BROWN, OF READING, MASSACHUSETTS.

AUTOMATICALLY-OPERATED STRINGED MUSICAL INSTRUMENT.

SPECIFICATION forming part of Letters Patent No. 678,318, dated July 9, 1901.

Application filed October 18, 1897. Serial No. 655,585. (No model.)

To all whom it may concern:

Be it known that I, DANA K. MARSHALL, of Manchester, in the county of Hillsboro and State of New Hampshire, have invented certain new and useful Improvements in Automatically-Operated Stringed Musical Instruments, of which the following is a specification.

This invention relates to automatically-operated stringed musical instruments in which the performance is governed by a progressively-moving actuator acting through suitable intermediate means upon string-vibrating devices and string-shortening fingers. 10 Heretofore the progressively-moving actuator has been a perforated sheet, the perforations in which either permit the closing of an electric circuit through which electrically-controlled mechanism is operated to move the 15 string-vibrating devices and fingers or to permit the movement of air-currents, which produce the same result through suitable pneumatic devices.

The present invention has for one object 20 to provide an apparatus of this character in which the progressively-moving actuator shall act mechanically to operate the string-vibrating devices and the string-shortening fingers.

The invention also has for its object to provide simple and effective means whereby the 25 strings of a violin may be automatically vibrated.

The invention consists in the several improvements which I will now proceed to describe and claim.

Of the accompanying drawings, forming a part of this specification, Figure 1 represents a front elevation of an automatic musical apparatus embodying my invention. Fig. 2 represents a rear elevation of the same. Fig. 3 represents a section on line 3-3 of Fig. 1. Fig. 4 represents a section on line 4-4 of Fig. 3. Figs. 4^a and 4^b represent modifications herein-after described. Fig. 5 represents an end elevation. Fig. 6 represents a view showing a portion of the base of the instrument in section and showing an elevation of parts of the mechanism shown in Fig. 5. Fig. 7 is a diagrammatic view representing the operation 50 of the string-vibrating bows or belts. Fig. 8 represents a side view, and Fig. 9 a top view,

of one form of progressively-moving actuating-surface embodying my invention. Figs. 10 and 11 represent, respectively, a side view and edge view of another form of actuating device embodying my invention. Figs. 12 and 13 represent modifications of the construction shown in Figs. 10 and 11. Fig. 14 represents a view showing the adaptation of my improvements to a banjo.

The same letters of reference indicate the same parts in all the figures.

In the drawings, *a* represents a base or bed having means for detachably holding a violin *b* or other musical stringed instrument, such as a banjo, mandolin, &c. In Figs. 1, 3, and 5 I show the base provided with vertical rods *a'*, having bent upper ends projecting over the body of the instrument *b* and provided with heads *a²*, having felt washers or faces 70 adapted to bear on the upper surface of the body of the instrument, the lower ends of the rods passing through the top of the base and being screw-threaded and provided with adjusting-nuts *a³*, (see Fig. 3,) whereby the 75 heads *a²* may be drawn down upon the instrument and caused to clamp it upon suitable seats provided upon the base.

When the instrument is a violin and requires to be played by a vibrator equivalent 80 to a bow drawn across its strings, I provide as the string-vibrating means two bands or belts *c c*, which I will call, for convenience, "belt-bows" and which extend across the instrument at the point where the bow is usually applied to the strings, and are supported by pulleys which are adjusted toward and from the instrument, so that the under side of each belt-bow can be depressed upon and raised from one or more of the strings. The 85 belt-bows *c c* may be made of any suitable material, leather or silk being preferred by me at the present time, although I do not limit myself to these materials. I prefer to arrange the belt-bows so that one of them is 90 adapted to act upon the two strings at one side of the series and the other upon the two strings at the opposite side. As shown in Figs. 5, 6, and 7, the two belt-bows run cross-wise of each other or at different angles, the 95 angle of the belt-bows accommodating them to the position of the strings. The belt-bows 100

are supported by pulleys c' , which are mounted to rotate upon standards c^2 c^3 , affixed to the base at opposite sides of the instrument b . One of the pulleys supporting each belt-bow is continuously rotated to give motion to its belt-bow by power applied in any suitable way, preferably from a driving-shaft c^3 , which may be driven by an electric motor or otherwise, and is connected by belts c^4 c^4 with the driven pulleys c' c' , as shown in Figs. 5 and 6.

The belt-bows c c are normally out of contact with the strings b of the instrument, and automatic mechanism is provided for applying either belt-bow to one or more of the strings by depressing the lower portion of the belt-bow from its normal position, so as to apply it to one or more strings, as indicated in Fig. 7, where the dotted lines show the normal positions of the belt-bows, the full lines showing the belt-bows depressed to act upon the strings. Said automatic mechanism includes a progressively-moving actuator, which may be a rotating cylinder d , as shown in Figs. 1, 2, and 3, or an endless belt or band d' , which may be a single sheet, as shown in Figs. 8 and 9, of any suitably strong and flexible material, such as leather-board, or an endless belt or band d'' , composed of a series of slats of rigid material flexibly connected, the slats being, for example, of wood cemented or otherwise secured to a continuous strip of canvas which flexibly connects the slats in a continuous band. When the actuator is a cylinder, it is moved progressively by the rotation of the cylinder, effected by any suitable means, preferably by the motor which actuates the belt-bow c c . When the actuator is an endless belt or band, as shown in Figs. 8 to 12, it is supported at suitable points by idle pulleys and is preferably driven by means of one or more sprocket-wheels d^4 , the teeth of which engage holes d^5 , formed for their reception in the said belt or band near its edges, as shown in Fig. 10. When the belt or band is constructed of slats, I prefer to make it separable at a suitable point in order that it may be conveniently applied and removed. The slats forming the ends of the series are provided with coupling members, whereby they may be detachably connected to form an endless band. In Figs. 10 and 11 I show one of the said slats provided with thin steel plates d^6 d^6 , permanently riveted at d^7 to one of the slats and overlapping the other slat and provided with orifices to receive the pins or projections d^8 on the last-mentioned slats. By springing the plates d^6 outwardly the end slats of the series may be disconnected, as will be readily seen. By thus providing means for breaking the continuity of the band or belt I am enabled not only to easily apply and remove it, but also to roll it in compact form when not in use.

65 The actuator, whether it be a cylinder or a belt or band, has suitable provisions for caus-

ing movement of a series of levers or other mechanical contrivances interposed between the said actuating-surface and the belt-bows and the string-pressing fingers hereinafter described, so that when the said actuator is moved progressively the bows and fingers will be operated in accordance with the scheme or program for which the actuator was prepared. The said provisions may be a series of pins or projections on the actuator or a corresponding series of slots, recesses, holes, or indentations in the surface of the actuator. In Figs. 1 and 3 I show pins or projections e radiating from the actuator, the latter being a cylinder. In Fig. 12 I show similar pins e' projecting from the actuator, the latter being a band or belt composed of strips. In Fig. 10 I show recesses or depressions e^2 formed in the actuator for the same purpose, and in Fig. 9 I show orifices e^3 . The said projections, recesses, or orifices are arranged to actuate the belt-bows and the fingers in any order or manner desired, each actuator being prepared to produce a given tune or musical performance, some of the projections, holes, or recesses being arranged to operate the belt-bows, while others are arranged to operate the fingers in a manner which will be readily understood.

The intermediate mechanism which communicates motion from the projections, holes, or recesses to the belt-bows and fingers may be organized in any suitable way. I have here shown said mechanism comprising in each case a lever f , which is normally pressed toward the actuator and is adapted to be displaced from its normal position by action of the projections. In the construction shown in Figs. 1 and 3 the levers f are pivoted at f' to ears on the base a , each lever having at one end a tooth or finger f^2 , projecting toward the actuator and adapted to be raised therefrom by contact with one of the projections e . To the opposite end of said lever is connected a cord, chain, or other flexible connecting device f^3 , which for convenience I will term a "cord." The cords of some of the levers f extend to the devices for raising and depressing the belt-bows, while the cords of other levers extend to the devices for depressing the fingers. Said cords f^3 are guided by suitable guiding-pulleys f^4 , the arrangement being such that whenever a lever f is displaced from its normal position by one of the projections e a pull will be exerted on the cord f^3 attached to that lever, and through said cord the belt-bow or finger intended to be operated thereby is moved to accomplish the desired result.

The fingers g are arranged in a series of groups, each group extending transversely across the neck of the instrument and comprising four fingers, one for each string. The groups of fingers are arranged at different distances from the bridge of the instrument, the number of groups being sufficient to pro-

vide for all the lengths of string required for producing the different notes of a musical composition. The fingers are attached to the bent ends of vertical rods g' , which extend through 5 guiding-orifices formed in holding-strips g^2 , preferably detachably secured by screws g^3 or otherwise to the sides of the neck of the instrument. The rods g' extend downwardly through brackets or guides g^4 , affixed to the 10 base a , and are attached at their lower ends to cords f^8 , the cords and their supporting-pulleys being arranged so that when a cord is pulled, as above described, the finger to which it is connected through the intermediate rod g' is depressed against the pressure of the springs g^5 . The fingers are normally raised from the strings by means of the said springs. The holding strips or sections g^2 , through which the finger-rods g' pass, are, as 15 already stated, detachably secured to the neck of the instrument, the object of this arrangement being to enable the fingers to be readily displaced from their position over the strings, and thus permit the instrument to be 20 readily removed from and applied to the base. 25

There being two of the holding strips or sections g^2 , each holding one-half of the fingers, the fingers over the two strings at one side may be displaced in one direction and those 30 at the opposite side may be displaced in the opposite direction, so that by a comparatively slight movement of the fingers they can be separated sufficiently to permit the raising of the neck of the instrument between them.

35 The bent ends of the rods g , to which the fingers are attached, are of different shapes, as shown in Fig. 1, the ends of every alternate rod being longer than the ends of the other rods and curved so as to bring the fingers of 40 each group into alignment across the neck of the instrument. It will be seen that by locating the vertical portions of the rods g outside the neck of the instrument and bending the upper ends of said rods over the neck I

45 am enabled to greatly simplify the construction of the fingers, each finger comprising a small button and a rod with a bent neck, to the end of which the button is secured. The button may be secured by simply driving the 50 end of the neck into it, the button being of wood or other compressible material.

The mechanism for raising and depressing the belt-bows includes, in addition to the levers f and cords f^3 , above described, arms f^5 , 55 pivoted at f^6 to the standards c^2 , each arm having at its swinging end two pulleys f^7 , bearing upon opposite sides of one of the belt-bows c , as shown in Fig. 5. The arms f^5 are normally held by springs f^8 in position to 60 hold the belt-bows out of contact with the strings. To each arm f^5 is connected a vertical rod f^9 , which passes downwardly through a guide in the base a and is connected at its lower end with one of the cords f^3 . The 65 arrangement of the cords f^3 and their guiding-pulleys, when pins or projections e are

employed on the actuator, is such that the above-described pull on the cord f^3 , caused by the displacement of the lever f by a pin, will depress the rod f^9 and swing downwardly 70 the arm f^5 , connected with said rod, thus depressing the belt-bow engaged with said arm and causing it to bear upon one or more of the strings. It should be here stated that each belt-bow is engaged with two of the arms 75 f^5 , one arm being at one side of the series of strings and the other at the opposite side. The two arms may be operated either independently or in unison. When only one arm f^5 is depressed, the belt-bow engaged therewith is depressed in such manner as to bear upon only one string; but when both arms f^5 are depressed simultaneously the bow is caused to bear simultaneously upon two strings. The belt-bow can be caused to bear 85 upon either of the two strings with which it coöperates by depressing either of the arms f^5 , leaving the other in its normal position. For example, referring to Fig. 7, the belt-bow can be engaged with the extreme right-hand string by depressing the right-hand arm, leaving the left-hand arm in its normal position. The belt-bow can be engaged with the second string from the right by depressing the left-hand arm, leaving the right-hand arm in 90 its normal position. It will be seen, therefore, that perfect control is exercised over the bows, the depression of the bows being determined by the arrangement of the projections on the actuator. 95

100 The pins or projections e' may be made of various forms and lengths, as shown in Fig. 13, where I show each pin provided with a shank adapted to be driven into the cylinder or into the slats, whereby the pins are supported and carried. The acting portions of the pins are preferably offset from the shanks, so that when the pins are used in a belt made of slats their acting portions may extend across cracks between the slats, if desired. 110

115 When the actuator is provided with recesses or holes instead of projections, the intermediate mechanism is arranged so that the belt-bows and the fingers will be pressed against the strings when the levers f are moved inwardly toward the actuator by sinking into the holes instead of outwardly, as is the case when pins or projections are employed. In Fig. 4^a I show an arrangement for operating the fingers when the levers f sink into 120 holes in the actuator, the finger-rods g' being extended inwardly beyond the adjacent guide-pulleys f^4 and the cords arranged so that when moved in the direction indicated by the arrow in Fig. 4^a they will raise the fingers from 125 the strings. Springs g^9 , interposed between the guides g^4 and collars g^{10} on the rods g' , exert pressure on the rods in the direction required to pull the cords f^3 in the direction opposite that indicated by the arrow in Fig. 130 4^a, thus causing the cords to press the levers f against the surface of the actuator. When

a lever coincides with a hole in the actuator, it sinks into the hole, thus permitting the spring g^9 to press the finger of the rod to which it is applied against the accompanying spring. The same arrangement may be employed for actuating the belt-bows, the springs f^8 , which act on the belt-controlling arms f^5 , being arranged, as shown in Fig. 4^b, to normally depress the belts instead of raising them.

- 10 In Figs. 5 and 6 I show means for applying resin to the belt-bows $c\ c$. i represents a box adapted to hold a cake i' of resin, said box being attached to an arm or lever i^2 , which is pivoted at i^3 to the standard c^2 and is provided at its outer end with a shoulder i^4 , which is in rolling contact with the belt-bow to be acted on by the resin. The arm i^2 may be pressed downwardly upon the bow either by gravitation or by a suitable spring i^6 . It will 20 be seen that the arms i^2 , bearing yieldingly on the belt-bows, act as tighteners to maintain the said bows at the proper degree of tension.

For the sake of automatic adjustability I 25 prefer to provide a spring connection between the levers f and the cords f^3 , so that the movement imparted by said levers and cords to the bows or to the fingers may be somewhat yielding, preventing strain on the parts in 30 case there is a tendency to move the bows or fingers downwardly farther than is required. In Fig. 3 I show this yielding connection in the form of a spring f^{12} , connecting the cord f^3 with the lever f . f^{13} and f^{14} , Fig. 5, represent adjusting-screws which limit the movements of the bow-adjusting arms f^5 , said screws enabling the up-and-down movements of the bow to be accurately adjusted.

In Fig. 14 I show means for vibrating or 40 picking the strings of a banjo, guitar, or mandolin, said means comprising a picker p , a moving actuator having projections e' , a lever f , arranged to be operated by said projections, and connections between said lever 45 and the picker. In this case said connections comprise a bell-crank lever p' , pivoted at p^2 to a bracket p^3 , affixed to the head of a banjo q , one arm of said lever being pivoted at p^4 to the shank of the picker p and a cord or 50 chain f^3 connecting the lever p' with the lever f . A spring p^5 , connected with the lever p' and bracket p^3 , normally forces the picker forward in the direction of the arrow shown in Fig. 14. The displacement of the lever f by the pin e' moves the picker in the opposite direction and causes it to vibrate the string. The picker has a pin p^6 , which moves in an elliptical slot or guide p^7 , arranged to give the picker an upward movement when 60 it is moved backwardly to pick the string and a downward movement when it is moved forward by the spring p^5 .

It is obvious that the arms f^5 , which raise and depress the belt-bows, may be operated 65 by any other suitable means and are not necessarily used in connection with an actu-

ator and intermediate connections of the character described.

I do not limit myself to the specific mechanism here shown, as the same may be variously modified without departing from the spirit of my invention.

When orifices e^3 are formed in the actuator, as shown in Fig. 9, or when depressions such as e^2 in Fig. 10 are employed, I prefer to 70 mount a roller or wheel on the end of the lever f , which wheel is adapted to ride into or out of said orifices or depressions. Such a wheel is illustrated in Figs. 8 and 9 and serves to facilitate the accurate operation of 80 the lever.

With the arrangement of cords, chains, or other flexible connections such as shown at f^3 in Fig. 14 I am enabled, by means of guiding-pulleys, such as f^4 , to extend the connections in any direction desired, so that different elements of the mechanism having different locations may be moved in different directions from one actuator and series of 90 levers.

I claim—

1. An apparatus of the character specified, comprising a lever, a progressively-moving actuator mechanically controlling said lever, a belt-bow and means for driving it, and connections between said bow and lever whereby the angular position or plane of movement of the bow is varied with the position of the lever.

2. An apparatus of the character specified, comprising two levers, a progressively-moving actuator mechanically controlling said levers, a belt-bow and means for driving it, and separate bow-moving connections between the levers and the bow, one lever being connected 105 with the bow near one end of its operating portion, while the other lever is connected with the bow near the other end of its operating portion.

3. An apparatus of the character specified, comprising a lever having a projection, a progressively-moving actuator against which the projection bears, a belt-bow extending across the strings of a musical instrument, a movable arm engaged with a portion of the bow 115 for deflecting that portion, and connections between said arm and lever.

4. An apparatus of the character specified, comprising a lever, a progressively-moving actuator mechanically controlling said lever, a belt-bow and means for driving it, means for adjusting the angle of the plane of movement of the operative portion of the bow, and a self-adjusting or elastic connection between the adjusting device and lever.

5. In an apparatus of the character specified, an actuating-band composed of a series of flexibly-connected slats or strips having pins or projections each comprising a penetrating shank and an acting portion offset 130 therefrom.

6. An apparatus of the character specified,

comprising a stringed musical instrument, two independent finger-guiding strips or sections detachably secured to opposite sides of the neck of the instrument, finger-bearing rods movable in said strips and having their outer ends bent inwardly over the strings, and means for reciprocating said rods.

5 In testimony whereof I have signed my

name to this specification, in the presence of two subscribing witnesses, this 30th day of 10 September, A. D. 1897.

DANA K. MARSHALL.
